UNITED STATES PATENT OFFICE.

ALAN ERNEST LEOFRIK CHORLTON, OF SWALLOWBECK, LINCOLN, ENGLAND.

INTERNAL-COMBUSTION ENGINE.

1,319,756.

Specification of Letters Patent.

Patented Oct. 28, 1919.

Application filed November 21, 1916. Serial No. 132,688.

To all whom it may concern:

Be it known that I, ALAN ERNEST LEOFRIK CHORLTON, a subject of the King of England, residing at Swallowbeck, Lincoln, in England, have invented certain new and useful Improvements in Internal-Combustion Engines, of which the following is a specification.

This invention relates to improvements in internal combustion engines whether of the revolving or stationary types and more especially air-cooled engines working on the six-stroke cycle which involves the use of "blind" strokes in the course of which air only is drawn into and expelled from the cylinder. The invention has for its object to obtain greater power and fuel economy as compared with engines of this type as usually constructed.

It is well known that the power developed in the cylinder of an air-cooled engine is limited by the rate at which heat produced in that cylinder can be dissipated and the extent of economy obtainable is determined by the low compression which it is necessary to employ in order to prevent pre-ignition in the heated cylinder. The normal method of cooling an air-cooled cylinder is to employ a number of thin and deep ribs attached to or integral with the cylinder itself and these ribs are subject to a blast of air either specially produced for the purpose or, as in the case of an engine employed in aeronautical work, the cooling blast is derived from the propeller driven by the engine or brought about by the air passing over the engine when the aircraft is in flight.

It is obvious that the extent of cooling that can be effected by such external means as this quickly reaches a limit and hence in order to develop higher power and economy which involves the use of larger cylinders and higher compression, it is necessary to also cool the interior of the cylinder and in an efficient manner. This can be accomplished by employing the six-stroke cycle as the air drawn in and expelled from the cylinder during the fifth and sixth strokes in a six-stroke cycle effects the necessary internal cooling of the cylinder and piston crown. The resultant effect of employing the six-stroke cycle as regards power and economy is that though the power falls off per stroke in consequence of there being only one working stroke in six as compared with one work-

ing stroke in four, in the case of a four-stroke engine, the decrease in power is in fact only small because it then becomes possible to use higher mean pressures and higher compressions in consequence of the more effectual scavenging of the cylinder and the greater cooling thereof. This brings about a considerable improvement in the economy and a reduction in the fuel consumption.

In an engine operating on the six-stroke cycle according to this invention all or a portion of the air expelled from a cylinder during a blind stroke of its piston is employed for supercharging purposes. Preferably this air after it leaves the cylinder is cooled before it is employed as a supercharge and also means are provided for varying the amount of air which is used as a supercharge. Thus two out of the six piston strokes are used not only to pass air through the cylinder for the purpose of cooling it but also to effect the delivery of a whole or a portion of this air as a supercharge to another cylinder during or at the end of the main charge suction stroke in that cylinder. As mentioned the temperature of the air is reduced by suitable means before it is employed as a supercharge, this cooling being necessary owing to the temperature of the air having been raised during its passage through the cylinder wherein it acted as a cooling agent. On leaving the cylinder after thus performing its cooling action the air is led through one or more thin metallic pipes or connections so shaped or disposed that they may be acted upon by the air passing over the engine or through which the engine passes. The air charge is in this way so cooled that when added as a supercharge to the main charge it will not raise the temperature of the main charge or at any rate to an undesirable extent. In a multicylinder engine such valves and connections are provided between those cylinders which are either themselves disposed in correct angular relation to each other about the crank shaft axis or which contain pistons connected to cranks disposed in correct angular relation on the crank shaft, that the explosive charge drawn into each cylinder receives a supercharge of air from another cylinder from which this air is expelled during the blind or what is most commonly termed the sixth stroke of the piston in that

cylinder. By this means the volume of air in each cylinder is so increased as to allow of a corresponding increase in the quantity of fuel and increased power is developed at the same time. By suitable proportioning of the compression and air content the heat to be dissipated can be effectively controlled.

In aeronautical work when an aircraft is at such a height that the attenuation of the atmosphere is appreciable it is possible to increase the extent to which supercharging is employed in the engine. On the other hand for normal running of the engine at or near the earth it may be desirable to reduce the amount of the supercharge, as also when the engine is running at slower speeds and is throttled down in the usual way since in either case the inrush of the air constituting the supercharge may tend to so dilute the combustible mixture as to cause a misfire.

An engine constructed in accordance with this invention is therefore preferably provided with means for varying the amount of the supercharge which is added to the main charge.

Various devices may be employed for this purpose so that when the air charge leaves the first cylinder the whole or a variable portion of this charge can be permitted to enter the second cylinder wherein it is added to the main charge in that cylinder when a supercharge is required. Thus reduction of the compression of the working charge which may result from attenuation of the atmosphere surrounding the improved engine may be wholly or partially compensated for by supplying to the working charge a supplementary charge of air under pressure and in such variable quantity as to prevent the power of the engine falling off unduly.

Some means may also be provided for varying the amount of air in the main charge before it is admitted to the cylinder so that on occasion if the supercharge tends to dilute the combustible mixture unduly the main charge may be enriched. This control of the richness of the main charge may be effected separately or combined with the supercharge control device.

In the accompanying drawings which illustrate somewhat diagrammatically some examples of engines constructed in accordance with this invention,

Figure 1 is a sectional end elevation of a rotary engine with four cylinders radially disposed about the crank shaft.

Fig. 2 is an end elevation of an eight cylinder rotary engine.

Fig. 3 is a plan of an eight cylinder engine of the fixed type.

Fig. 4 is an end elevation of the same.

Fig. 5 is a longitudinal sectional elevation in the plane of the crank shaft axis illustrating a part of an eight cylinder engine,

such as shown in Fig. 2, and more particularly one method of controlling the valves so as to effect variation in the amount of the supercharge.

Fig. 6 is an elevation of one of the adjustable cams employed in the construction shown in Fig. 5.

Like letters indicate like parts throughout the drawings.

Referring to Fig. 1 the cylinders A are mounted in some suitable known or other manner on the crank casing B being arranged so as to radiate from the crank shaft axis C. In the construction illustrated in this figure four cylinders only are shown as being more convenient for the explanation of the invention. One or more ports A' are formed in each cylinder toward its outer end and in such a position that they will be uncovered by the piston D when it is nearing the end of its outstroke as shown in cylinder No. 1 in Fig. 1. These ports open into an annular chamber E which surrounds the cylinder A toward its open end. The chamber E may be formed in one with the cylinder or as shown in Fig. 1 it is formed integral with the crank casing B. Leading into each chamber E is a pipe F which runs from the head of the next adjacent cylinder in the construction shown in Fig. 1. In the eight cylinder engine shown in Fig. 2, however, the pipes F in each case run between alternate cylinders as will be explained later.

In the head of the cylinder A is an opening A² which is controlled by a valve G and communicates with the end of the pipe F in some convenient way. Preferably the opening A² is that through which the exhaust products of combustion pass from the cylinder and the valve G is the ordinary exhaust valve, some means being provided which allow the exhaust products to pass out into the air but permit the whole or a variable portion of the air charge to pass into the pipe F when this air is expelled from the cylinder. Various devices may be employed for this purpose so as to control and vary the amount of the supercharge. One such device is shown as applied to cylinder No. 1 in Fig. 1 and comprises a valve in the form of a disk G' which is carried on the stem G² of the valve G. On the head of the cylinder A around the opening or port A² is disposed a tube or sleeve H which constitutes a short passage or chamber into which the exhaust opening A² leads. The end of this sleeve H is open and forms a seating for the valve G' and from an opening in the side of the chamber leads the pipe F. Opposite the end of the valve stem G² is arranged a lever J which is so moved by cams as the cylinders rotate about the crank shaft that by this lever the valve stem G² will be pushed inward against the action of a spring controlling it. The cam operating

100

115

120

125

130

the lever J is so formed that the first movement imparted to the valve stem G² is sufficient to lift the valve G off its seat but not enough to bring the valve G' on to its seat. 5 The valves now occupy the position in which they are shown in cylinder No. 3. The passage through the port A² and sleeve H is now open for the products of combustion to escape into the atmosphere during what may 10 be termed the fourth stroke of the piston D. During the next or fifth stroke of the piston the valve G is still kept open to the same extent so that air can be drawn freely into the cylinder. At the next or sixth stroke 15 of the piston however further inward movement is imparted to the valve stem G² sufficient to bring the valve G' down on its seat and thus close the opening to the atmosphere. The air contained in the cylinder is now 20 pressed and passes through the pipe F into the other cylinder as soon as the piston in that cylinder has moved on its outstroke sufficiently far to uncover the ports A' of that cylinder. The piston of this second cylinder is at this time completing its first or 25 charging stroke when the charge of combustible mixture has been drawn into the cylinder. Consequently at the end of this stroke the supercharge of air is added to the 30 main charge and the piston then compresses this charge which is subsequently fired.

If it is desirable not to pass the whole of the air charge into another cylinder where it will act as supercharge, the movement of the valves G and G' may be so varied that either the whole of the air charge will pass again into the atmosphere at the sixth stroke of the piston or by partially closing the valve G a certain amount of this 40 air charge will be allowed to escape into the atmosphere while the remainder will pass as a supercharge of smaller volume into the other cylinder. The mechanism by means of which this variation may be effected in 45 the amount of air passing as a supercharge from one cylinder to another may comprise different constructions which are operated as found desirable.

The valves which control the supercharge 50 may be actuated in different ways which permit of the necessary variation or regulation of their movements. For example the cams operating the valves may be so arranged as to be adjustable the adjustment being effected directly or otherwise. Thus 55 the supercharging cam may be so combined with an exhaust cam that movement of the one with relation to the other will vary the duration of the full lift imparted to the 60 valve G G' by the conjoint operation of these cams through the lever J. A construction embodying this feature is illustrated in Figs. 5 and 6. In the preferred 65 arrangement of radial engine constructed according to this invention the cylinders A

and the crank shaft K revolve in opposite directions. A fixed member L carries pins L' which gear on the one hand with an externally toothed ring K' mounted on the crank shaft and on the other hand with an internally toothed ring B' mounted on the revolving casing B which carries the cylinders. The fixed member L is provided with a cylindrical part L² on which are disposed the cams. These are eight in number and 70 operate the valves of all the eight cylinders. Four of these cams M control the inlet valves and four of them N control the exhaust and supercharging valves G G' each cam operating two valves. Each of the 75 cams N is formed in two parts the main portion, like the cams M, being fixed to the member L² while a part N' of each exhaust cam is loosely mounted on member N² so as to be rotatable to a limited extent about 80 the member L². It will be seen by reference to Fig. 6 that the main operative part N of each exhaust cam is of a certain uniform height which acting through the rod J' and lever J is sufficient to lift and maintain the 85 valve G off its seat but not sufficient to seat the valve G'. As already explained this allows the exhaust gases or the air from the blind stroke to pass freely out of each cylinder A. The operative face of this cam is 90 also provided with a portion N² of greater height which is sufficient to impart to the valve spindle G² the additional movement necessary to bring the valve G' on to its seat. In order to enable the time to be varied during 95 which this valve is maintained on its seat and so to vary the amount of air which passes from one cylinder into another as a supercharge the separate cam part N' is provided of the same height as the part N² of 100 the main cam and adjustable in relation to it. It will be apparent that by rotational movement of the part N' the circumferential length of the higher portion of the whole cam can be increased or decreased. 105 The end of the valve rod J' is of sufficient width to bear on both parts N' and N² each of which is conveniently half the width of 110 the main part N of the cam.

All the adjustable parts N' of the exhaust 115 cams N are connected by one or more longitudinal keys or members N³ which also serve to couple these cam parts N' to a toothed ring N⁴ loosely mounted on the fixed member L². The members N³ are cylindrical in 120 shape and are loosely mounted on member L². Thus by rotation of the ring N⁴ all the cam parts N' can be moved simultaneously and relatively to the parts N which are fixed on the part L². 125

The movement of the part N' may be effected in the following manner. On a cylindrical part B² of the rotating crank casing B is mounted a toothed ring O which does not rotate with the part B² but can be 130

shifted about the latter to a limited extent by means of a lever O' which projects through an opening L^3 in a part of the fixed member L . This lever may be operated by 5 worm gearing or otherwise so that it will be locked in whatever position it is set. In a suitable bearing B^3 mounted on the rotating crank casing B is carried a spindle P on each end of which are fixed gear 10 wheels P' P^2 of equal size. The wheel P' engages the toothed ring N^4 while the wheel P^2 gears with the ring O . One or more spindles P and gear wheels P' P^2 may be provided and while these spindles are all 15 carried around by the crank case B as it rotates about the fixed member L the wheels P' P^2 remain in mesh with the rings N^4 and O . Thus any rotational movement of the ring O will be transmitted through the 20 spindles P to the ring N^4 so that the cam parts N' can be thereby moved and set to bring about the delivery of the required amount of supercharge to each cylinder.

An engine constructed in accordance with 25 this invention and having eight radial rotating cylinders is provided with four exhaust cams and four inlet control cams while four supercharging cams coöperate with the exhaust cams.

30 Alternatively the necessary variation in the amount of the supercharge may be brought about by suitable control of the air as it passes into the cylinder at the fifth or air suction stroke of the piston therein.

35 The cycle of operations performed by the engine illustrated in Fig. 1 may now be indicated. For convenience the cylinders will be respectively referred to by the numbers 1 to 4 reading clockwise as the engine is viewed in the drawing but it is to be noted 40 that as indicated by the arrow the cylinders actually rotate in a counter clockwise direction about the crankshaft. The successive strokes of each piston and the functions performed during each of these strokes may be 45 designated as follows:—The first stroke, in an outward direction, is the charging stroke when the main combustible charge is drawn into the cylinder. The second stroke, in an 50 inward direction, compresses the complete combustible charge. The third stroke, an outward one, occurs after the charge has been fired and while expansion is taking place. During the fourth stroke the exhaust 55 products of combustion are expelled. The fifth stroke, an outward one, draws in the charge of air the whole or a part of which is subsequently used as a supercharge. During 60 the sixth stroke this air charge is expelled from the cylinder and passes wholly or partially thence into another cylinder.

In cylinder No. 1 as shown in Fig. 1, the valve G is closed and the piston has completed its first stroke and is about to commence its second stroke when the combus-

tible charge with which the cylinder is filled will be compressed. In cylinder No. 2 the piston is performing its third stroke. In cylinder No. 3 the piston has just finished the fourth stroke and is about to begin its 70 fifth stroke. In cylinder No. 4 the piston is performing its sixth stroke. It will be noted that in cylinder No. 1 the ports A' are fully uncovered by the piston and hence the air charge which has been somewhat 75 compressed in the cylinder No. 4 is able to pass as a supercharge into the cylinder No. 1.

Let it now be assumed that the valve G in cylinder No. 1 is open to the extent shown in cylinder No. 3 that is to say not sufficiently to bring the valve G' on to its seat. The gases in the cylinder can now escape freely to the atmosphere and the piston may therefore be taken as having just completed its third stroke and about to commence its 80 fourth stroke, when the products of combustion will be exhausted. The piston in cylinder No. 2 will then be performing its fifth stroke. In cylinder No. 3 the piston has just finished its sixth stroke and is about 85 to begin its first stroke. In cylinder No. 4 the piston is performing its second stroke.

Finally let it be assumed that the valve G in cylinder No. 1 is fully open and the valve G' on its seat. The cylinder is now 95 filled with air as the piston may be taken to have just completed its fifth stroke and to be about to begin its sixth stroke when the air charge will be at first compressed and then forced along the pipe F into the cylinder No. 2. In this latter cylinder the piston is now performing its first stroke. The piston in cylinder No. 3 has just finished its second stroke and is about to commence its 100 third stroke. In cylinder No. 4 the piston is performing its fourth stroke.

It will thus be apparent that during the fifth and sixth strokes of the piston by suitable manipulation of the valves G and G' or of other valves or convenient devices the 110 amount of air which is allowed to pass into each cylinder as a supercharge may be varied or the supercharging can be stopped altogether. It will also be seen that by suitable disposition of the pipes F the air passing through these pipes can be cooled either by inducing a current of air to pass over the pipes or by the passage of the whole engine through the air as when employed on an aircraft. Also the cooling effect may 115 be enhanced by suitable formation of the pipes F .

Turning now to Fig. 2 where an eight cylinder engine is shown it will be noted that the pipes F in this case lead from one 125 cylinder to the chamber E of the next cylinder but one. This construction is in effect a duplication of the four cylinder engine shown in Fig. 1 as the cylinders are grouped in fours the cylinders forming each group 130

being disposed relatively at angles of 90° about the crank shaft axis. Hence the air charge from cylinder No. 1 passes as a supercharge into cylinder No. 3 while the air charge from No. 3 passes to No. 5, that from No. 5 into No. 7 and finally the air charge from No. 7 to No. 1. Similarly the air charges from the cylinders Nos. 2, 4, 6 and 8 pass from one to the other of these cylinders. If Fig. 2 is regarded as the front view of the engine as mounted on an aeroplane it will be seen that the disposition of the pipes F is favorable to the passage of air over these pipes so as to effect the desired cooling of the air as it passes through them.

It will be understood that the pipe connections may be otherwise arranged between the cylinders, the number of which may vary provided that the cylinders thus connected by the pipes F are disposed in correct angular relation about the crank shaft axis so that the explosive charge drawn into each cylinder can receive a supercharge of air from another cylinder, the valves or other control devices being preferably so arranged that the amount of this supercharge can be varied.

The engine illustrated in Figs. 3 and 4 is of the fixed cylinder type. The cylinders are arranged in groups of four and all the cylinders in a group are disposed with their axes in the same plane relatively to the crank shaft. The pipe connections F for conveyance of the supercharges lead from one cylinder in a group to the next adjacent cylinder in that group except that the pipe F leading from the cylinder at one end of the row is carried to the chamber E of the cylinder at the other end of the group row. The cranks to which are connected the pistons in the cylinders forming a group, are disposed in correct angular relation so that each cylinder will in turn receive a supercharge as and when determined by the supercharge control mechanisms. The groups of cylinders may be relatively arranged as found desirable with respect to the crank shaft axis.

It is sometimes customary in eight cylinder rotary engines to arrange that the firing of the charges in the cylinders does not take place consecutively but in cylinders which are equally spaced apart as for example in cylinders taken in the following order:—1, 4, 7, 2, 5, 8 and so on. In applying the present invention to an engine so arranged the valves and connections between the cylinders are such that one group of cylinders equally spaced apart for example Nos. 1, 4 and 7 are coupled to another group equally spaced apart such as 2, 5 and 8 so that the explosive charge drawn into a cylinder in one group receives a supercharge of air from a cylinder in another group

from which latter cylinder this air is expelled at the sixth or equivalent stroke of its piston.

It is to be noted that whereas the supercharge has mainly been referred to above, chiefly for convenience of description, as being comprised of air only, yet in some cases to which the invention is applicable it may be convenient or desirable to employ a combustible mixture. It is to be understood therefore that the use of a charge of such mixture may be used in place of air only and the appended claims are to be interpreted accordingly.

The details of construction may be varied in accordance with requirements.

What I claim as my invention and desire to secure by Letters Patent is:—

1. In an internal combustion engine operating on the six stroke cycle the combination of a plurality of cylinders, and valve controlled conduits between the cylinders so arranged that air expelled from one cylinder during a blind stroke of the piston therein is conveyed to another cylinder in which it constitutes a supercharge as set forth.

2. In an internal combustion engine operating on the six stroke cycle the combination of a plurality of cylinders, valve controlled conduits between the cylinders so arranged that air expelled from one cylinder during a blind stroke of the piston therein is conveyed to another cylinder in which it constitutes a supercharge, and means for cooling the air passing through the conduits as set forth.

3. In an internal combustion engine operating on the six stroke cycle the combination of a plurality of cylinders, valve controlled conduits between the cylinders so arranged that air expelled from one cylinder during a blind stroke of the piston therein is conveyed to another cylinder in which it constitutes a supercharge, and means for varying the amount of air which passes as a supercharge from one cylinder to another as set forth.

4. In an internal combustion engine operating on the six stroke cycle the combination of a plurality of cylinders, valve controlled conduits between the cylinders so arranged that air expelled from one cylinder during a blind stroke of the piston therein is conveyed to another cylinder in which it constitutes a supercharge, means for cooling the air passing through the conduits, and means for varying the amount of air which passes as a supercharge from one cylinder to another as set forth.

5. In an internal combustion engine operating on the six stroke cycle the combination of a plurality of cylinders, and valve controlled conduits between the cylinders so arranged that air expelled from one cyl-

inder during a blind stroke of the piston therein is conveyed to another cylinder in which it constitutes a supercharge, the conduits being disposed between the cylinders 5 so that air passing over the engine will exercise a cooling effect on the conduits and on the air charges passing through them as set forth.

6. In an internal combustion engine operating on the six stroke cycle the combination of a plurality of cylinders, valve controlled conduits between the cylinders so arranged that air expelled from one cylinder during a blind stroke of the piston therein 10 is conveyed to another cylinder in which it constitutes a supercharge the conduits being disposed between the cylinders so that air passing over the engine will exercise a cooling effect on the conduits and on the air 15 charges passing through them, and means for varying the amount of air which passes as a supercharge from one cylinder to another as set forth.

7. In an internal combustion engine operating on the six stroke cycle the combination of a plurality of cylinders, a valve controlled exhaust port in the head of each cylinder, inlet ports in the length of each cylinder, and a plurality of conduits each leading 25 from the exhaust port in one cylinder to the said inlet ports of another cylinder these conduits serving to convey the air expelled from one cylinder during a blind stroke of the piston therein to another cylinder in 30 which it constitutes a supercharge as set forth.

8. In an internal combustion engine operating on the six stroke cycle the combination of a plurality of cylinders, a valve controlled exhaust port in the head of each cylinder, inlet ports in the length of each cylinder, a plurality of conduits each leading from the exhaust port in one cylinder to the said inlet ports of another cylinder these 40 conduits serving to convey the air expelled from one cylinder during a blind stroke of the piston therein to another cylinder in which it constitutes a supercharge, and means for varying the amount of air which 45 passes as a supercharge from one cylinder to another as set forth.

9. In an internal combustion engine operating on the six stroke cycle the combination of a plurality of cylinders, a valve controlled exhaust port in the head of each cylinder, inlet ports in the length of each cylinder, and a plurality of conduits each leading from the exhaust port in one cylinder to the inlet ports of another cylinder 55 these conduits serving to convey the air expelled from one cylinder during a blind stroke of the piston therein to another cylinder in which it constitutes a supercharge the conduits also being disposed between the 60 cylinders so that air passing over the engine 65

will exercise a cooling effect on the conduits and on the air charges passing through them as set forth.

10. In an internal combustion engine operating on the six stroke cycle the combination of a plurality of cylinders, a valve controlled exhaust port in the head of each cylinder, inlet ports in the length of each cylinder, a plurality of conduits each leading from the exhaust ports in one cylinder to 70 the inlet ports in another cylinder these conduits serving to convey the air expelled from one cylinder during a blind stroke of the piston therein to another cylinder in which it constitutes a supercharge the conduits also 75 being disposed between the cylinders so that air passing over the engine will exercise a cooling effect on the conduits and on the air charges passing through them, and means for varying the amount of air which passes 80 as a supercharge from one cylinder to another as set forth.

11. In an internal combustion engine operating on the six stroke cycle the combination of a plurality of cylinders, a valve controlled exhaust port in the head of each cylinder, a chamber into which this exhaust port opens, a valve controlled port leading from this chamber to the atmosphere, inlet ports in the length of each cylinder, and a 90 plurality of conduits each leading from the said exhaust chamber of one cylinder to the said inlet ports of another cylinder these conduits serving to convey the air expelled from one cylinder during a blind stroke of 95 the piston therein to another cylinder in which it constitutes a supercharge as set forth.

12. In an internal combustion engine operating on the six stroke cycle the combination of a plurality of cylinders, a valve controlled exhaust port in the head of each cylinder, a chamber into which this exhaust port opens, a valve controlled port leading from this chamber to the atmosphere, inlet 105 ports in the length of each cylinder, a plurality of conduits each leading from the said exhaust chamber of one cylinder to the said inlet ports of another cylinder these conduits serving to convey the air expelled from 110 one cylinder during a blind stroke of the piston therein to another cylinder in which it constitutes a supercharge, and means for varying the amount of air which passes as a 115 supercharge from each exhaust chamber 120 through a conduit to another cylinder as set forth.

13. In an internal combustion engine operating on the six stroke cycle the combination of a plurality of cylinders, a valve controlled exhaust port in the head of each cylinder, a chamber into which this exhaust port opens, a valve controlled port leading from this chamber to the atmosphere, inlet 125 ports in the length of each cylinder, and a 130

plurality of conduits each leading from the said exhaust chamber of one cylinder to the said inlet ports of another cylinder these conduits serving to convey the air expelled 5 from one cylinder during a blind stroke of the piston therein to another cylinder in which it constitutes a supercharge the conduits also being disposed between the cylinders so that air passing over the engine will 10 exercise a cooling effect on the conduits and on the air charges passing through them as set forth.

14. In an internal combustion engine operating on the six stroke cycle the combination of a plurality of cylinders, a valve controlled exhaust port in the head of each cylinder, a chamber into which this exhaust port opens, a valve controlled port leading from this chamber to the atmosphere, inlet 15 ports in the length of each cylinder, a plurality of conduits each leading from the said exhaust chamber of one cylinder to the said inlet ports of another cylinder these conduits serving to convey the air expelled 20 from one cylinder during a blind stroke of the piston therein to another cylinder in which it constitutes a supercharge the conduits also being disposed between the cylinders so that air passing over the engine will 25 exercise a cooling effect on the conduits and on the air charges passing through them, and means for varying the amount of air which passes as a supercharge from each exhaust chamber through a conduit to another 30 cylinder as set forth.

15. In an internal combustion engine operating on the six stroke cycle the combination of a plurality of cylinders, an exhaust port in the head of each cylinder, a chamber into which this exhaust port opens, a port leading from this chamber to the atmosphere, a valve controlling each of said exhaust ports, a valve controlling each of said ports leading to the atmosphere, a spindle 40 on which said valves are mounted in pairs the valves being constructed and arranged so that they are respectively seated by movements on the spindle in opposite directions so that when one valve is on its seat the 45 other is lifted and both can also be simultaneously maintained off their seats, means for imparting movement to the spindle and operating the valves, inlet ports in the length of each cylinder, and a plurality of conduits 50 on which said valves are mounted in pairs the valves being constructed and arranged so that they are respectively seated by movements on the spindle in opposite directions so that when one valve is on its seat the 55 other is lifted and both can also be simultaneously maintained off their seats, means for imparting movement to the spindle and operating the valves, inlet ports in the length of each cylinder, and a plurality of conduits 60 each leading from the said exhaust chamber of one cylinder to the said inlet ports of another cylinder these conduits serving to convey the air expelled from one cylinder during a blind stroke of the piston therein to another cylinder in which it constitutes a supercharge as set forth.

16. In an internal combustion engine operating on the six stroke cycle the combination of a plurality of cylinders, an exhaust 65 port in the head of each cylinder, a chamber

into which this exhaust port opens, a port leading from this chamber to the atmosphere, a valve controlling each of said exhaust ports, a valve controlling each of said ports leading to the atmosphere, a spindle on 70 which said valves are mounted in pairs the valves being constructed and arranged so that they are respectively seated by movements of the spindle in opposite directions so that when one valve is on its seat the 75 other is lifted and both can also be simultaneously maintained off their seats, means for imparting movement to the spindle and operating the valves, means for varying this movement and the operation of the valves 80 so as to vary the amount of air which passes as a supercharge from one cylinder to another, inlet ports in the length of each cylinder, and a plurality of conduits each leading from the said exhaust chamber of one cylinder 85 to the said inlet ports of another cylinder these conduits serving to convey the air expelled from one cylinder during a blind stroke of the piston therein to another cylinder in which it constitutes a supercharge as 90 set forth.

17. In an internal combustion engine operating on the six stroke cycle the combination of a plurality of cylinders, an exhaust port in the head of each cylinder, a chamber into which this exhaust port opens, a port leading from this chamber to the atmosphere, a valve controlling each of said exhaust ports, a valve controlling each of said ports leading to the atmosphere, a spindle on 95 which said valves are mounted in pairs the valves being constructed and arranged so that they are respectively seated by movements of the spindle in opposite directions so that when one valve is on its seat the other is lifted and both can also be simultaneously maintained off their seats, means for imparting movement to the spindle and operating the valves, inlet ports in the length of each cylinder, and a plurality of conduits each leading from the said exhaust chamber of one cylinder to the said inlet ports of another cylinder these conduits serving to convey the air expelled from one cylinder during a blind stroke of 100 the piston therein to another cylinder in which it constitutes a supercharge the conduits also being disposed between the cylinders so that air passing over the engine will 105 exercise a cooling effect on the conduits and on the air charges passing through them as set forth.

18. In an internal combustion engine operating on the six stroke cycle the combination of a plurality of cylinders, an exhaust port in the head of each cylinder, a chamber into which this exhaust port opens, a port leading from this chamber to the atmosphere, a valve controlling each of said exhaust ports, a valve controlling each of 115

said ports leading to the atmosphere, a spindle on which said valves are mounted in pairs the valves being constructed and arranged so that they are respectively seated by movements of the spindle in opposite directions so that when one valve is on its seat the other is lifted and both can also be simultaneously maintained off their seats, means for imparting movement to the spindle and operating the valves, means for varying this movement and the operation of the valves so as to vary the amount of air which passes as a supercharge from one cylinder to another, inlet ports in the length of each cylinder, and a plurality of conduits each leading from the said exhaust chamber of one cylinder to the said inlet ports of another cylinder these conduits serving to convey the air expelled from one cylinder during a blind stroke of the piston therein to another cylinder in which it constitutes a supercharge the conduits also being disposed between the cylinders so that air passing over the engine will exercise a cooling effect on the conduits and on the air charges passing through them as set forth.

19. In an internal combustion engine operating on the six stroke cycle the combination of a plurality of cylinders the pistons in which operate on a common crank shaft in such angular relation that the cylinders can be coupled in pairs so that when the piston in one cylinder of a pair is performing a blind stroke and expelling air the piston in the other cylinder of the pair is performing its charging stroke, and valve controlled conduits coupling the cylinders in such pairs each conduit serving to convey air when expelled from the one cylinder to the other cylinder of the pair in which it constitutes a supercharge as set forth.

20. In an internal combustion engine operating on the six-stroke cycle the combination of a plurality of cylinders the pistons in which operate on a common crank shaft in such angular relation that the cylinders can be coupled in pairs so that when the piston in one cylinder of a pair is performing a blind stroke and expelling air the piston in the other cylinder of the pair is performing its charging stroke, and valve controlled conduits coupling the cylinders in such pairs each conduit serving to convey air when expelled from one cylinder to the other cylinder of the pair in which it constitutes a supercharge the conduits being disposed between the cylinders so that air passing over the engine will exercise a cooling effect on the conduits and on the air charges passing through them as set forth.

21. In an internal combustion engine operating on the six stroke cycle the combina-

tion of a plurality of cylinders the pistons in which operate on a common crank shaft in such angular relation that the cylinders can be coupled in pairs so that when the piston in one cylinder of a pair is performing a blind stroke and expelling air the piston in the other cylinder of the pair is performing its charging stroke, valve controlled conduits coupling the cylinders in such pairs each conduit serving to convey air when expelled from the one cylinder to the other cylinder of the pair in which it constitutes a supercharge, and means for varying the amount of air which passes as a supercharge from one cylinder to another as set forth.

22. In an internal combustion engine operating on the six stroke cycle the combination of a plurality of cylinders the pistons in which operate on a common crank shaft in such angular relation that the cylinders can be coupled in pairs so that when the piston in one cylinder of a pair is performing a blind stroke and expelling air the piston in the other cylinder of the pair is performing its charging stroke, valve controlled conduits coupling the cylinders in such pairs each conduit serving to convey air when expelled from one cylinder to the other cylinder of the pair in which it constitutes a supercharge the conduits being disposed between the cylinders so that air passing over the engine will exercise a cooling effect on the conduits and on the air charges passing through them, and means for varying the amount of air which passes as a supercharge from one cylinder to another as set forth.

23. In an internal combustion engine operating on the six stroke cycle, in which air is compressed and expelled during a blind stroke of the engine, means for utilizing such compressed air as a supercharge at the termination of a succeeding charging period, and means for cooling such air prior to its re-admission.

24. In an internal combustion engine operating on the six stroke cycle, the combination with a plurality of cylinders, each having a piston therein, of means for utilizing as a supercharge in each cylinder air expelled from a cylinder during a blind stroke of the piston therein, and means for cooling such air prior to its admission as a supercharge.

In witness whereof I have signed my name to this specification in the presence of two subscribing witnesses.

ALAN ERNEST LEOFRIE CHORLTON.
